UNITED STATES PATENT OFFICE

2,596,589

RADIATOR ASSEMBLY FOR INTERNAL-COMBUSTION ENGINES AND THE LIKE

Robert O. Nusbaum, Elkhart, Ind.

Application October 21, 1949, Serial No. 122,789

3 Claims. (Cl. 257—125)

1

This invention relates to improvements in radiator assemblies for internal combustion engines and the like.

The main objects of this invention are:

First, to provide a radiator assembly for internal combustion engines and the like which permits the effective inspection and cleaning of the core or heat exchange unit without the necessity for removing the tank or header from the heat exchange unit.

Second, to provide a radiator assembly for internal combustion engines and the like with a screen which can be readily removed for cleaning or replacement.

Third, to provide a structure embodying these advantages which permits effective servicing by relatively unskilled workmen.

Objects relating to details and economies of the invention will appear from the description to follow. The invention is pointed out in the claims.

A preferred embodiment of the invention is illustrated in the accompanying drawing, in which:

Fig. 1 is an enlarged fragmentary view in vertical section on a line corresponding to line 1—1 of Fig. 2.

Fig. 2 is a fragmentary plan view with parts of the cover or closure of the tank or header being broken away to illustrate the relation to the heat exchange unit.

Fig. 3 is a fragmentary elevational view of a modified form or embodiment of my invention.

The embodiment of my invention illustrated in the accompanying drawing comprises a heat exchange unit or core 1 comprising a plurality of finned vertical tubes 2. The tank or header 3 has an opening 4 in the bottom thereof preferably surrounded by the upwardly projecting flange 5. This tank or header 3 is fixedly secured to the heat exchange unit as by soldering or other suitable means as is indicated at 6. The opening 4 in the bottom of the header is of such dimensions as to embrace all of the tubes of the heat exchange unit. The top wall 7 of the header is provided with an elongated opening 8, the edge around the opening being downwardly offset at 9 providing an upwardly facing gasket seat 10 for the gasket 11. The closure or cover 12 is upwardly offset at 13 to provide a downwardly facing gasket seat 14 receiving the gasket. A plurality of turn button type latches 15 are provided, these being mounted on threaded studs 16 slotted at 161 to receive a tool to permit the latches being turned to engaging position as shown in Fig. 1 in which position the cover is

2

clamped by the thumb nut 17. The reverse manipulation releases the cover. The opening 8 in the header is of such dimensions as to permit inspection of the tubes and the "rodding" or cleaning thereof by means of a rod-like implement.

In the embodiment shown in Figs. 1 and 2 the filling opening provided with a cap 18 is disposed at one end of the opening 8. In the embodiment shown in Fig. 3 the closure 19 is provided with the filling opening closed by the cap 20.

The rear wall of the header is provided with a nipple 21 disposed centrally thereof and adapted to receive the return conduit or hose 22 secured thereon by means of the hose clamp 23. The tubular screen 24 is desirably elongated and is provided with a tubular coupling 25 fixedly secured thereto and projecting into the screen, the coupling being provided with a downwardly facing discharge 26 and being desirably arranged centrally of the screen relative to its length. This connection 21 serves as a support for the screen. With this arrangement the return water is effectively screened and as desired or when necessary the screen can be removed for cleaning or replacement.

To prevent the screen becoming disengaged I provide the cover with the depending finger 29 which engages the screen and prevents the coupling 25 becoming disengaged from the nipple 21. The flange 5 around the opening 4 in the bottom of the header provides a sediment trap 27 which is accessible for cleaning when the closure of the header is removed. With this arrangement of parts the radiator can be effectively cleaned without removing from the engine and without removing the tank or header from the core or heat exchange unit. It is desirable in use that the cooling medium in the system shall be sufficient to keep the header at least partially filled, this being necessary to secure the proper distribution of the water throughout the core. The coupling 25 is provided with a baffle 28 at its inner end which serves not only to direct the water downwardly in the header but tends to spread it out as delivered.

Structures embodying my invention may be effectively serviced by relatively unskilled persons and in a fraction of the time that is necessary to service radiators which become clogged and require the dismounting and remounting on the vehicle and the removal and replacement of the header in order to effectively clean the core or heat exchange unit. Such removal requires unsoldering and resoldering which requires great

skill and care in order to prevent damage to the core and to avoid leaks when the work has been completed.

I have illustrated and described my invention in highly practical embodiments thereof. I have not attempted to illustrate or describe other embodiments or adaptations as it is believed that this disclosure will enable those skilled in the art to embody or adapt my invention as may be desired.

Having thus described my invention, what I claim as new and desire to secure by Letters Patent is:

1. The combination of a heat exchange unit comprising a plurality of tubes, a sheet metal tank constituting a header for said tubes and having an opening in its top wall extending the major portion of the length thereof, the edge around the opening being downwardly offset providing a gasket seat, a sheet metal cover for said opening having a downwardly facing gasket seat at its edge, a gasket arranged on said seat of said tank to be received in said seat of said cover, a plurality of latches spacedly mounted on said cover and turnable to engage the underside of the tank top, a nipple disposed on the rear wall of the tank and adapted to constitute a connection for a return circulating conduit to the unit, a tubular screen provided with a tubular coupling fixedly secured at right angles to said screen and constituting a support for the screen, said coupling being telescopingly engaged in said nipple and being provided with a downwardly directed discharge positioned centrally within the screen, and a depending finger on said cover engaging the screen when the cover is in position to prevent the withdrawal of the coupling from the nipple.

2. The combination of a heat exchange unit comprising a plurality of tubes, a sheet metal tank constituting a header for said tubes and having an opening in its top wall extending the major portion of the length thereof, a cover for said opening, means removably securing said cover to said tank, a return circulation connection opening to said tank, a tubular screen pro-

vided with a coupling fixedly secured thereto and constituting a support for the screen, said coupling being telescopingly engaged with said return circulation connection, and means on the cover engageable with said screen for preventing disengagement of the coupling when the cover is in closed position.

3. The combination of a heat exchange unit comprising a plurality of tubes, a sheet metal tank constituting a header for said tubes and having an opening in its top wall extending the major portion of the length thereof, a cover for said opening, a plurality of latches spacedly mounted on said cover and turnable to engage the underside of the tank top, a return circulation connection opening to said tank, and a tubular screen provided with a tubular coupling discharging within the screen fixedly secured thereto and constituting a support element for the screen, said coupling being supportingly engaged with said return circulation connection, said screen being removable bodily from said tank through the opening therein and without distortion.

ROBERT O. NUSBAUM.
